SCREW DRIVER

Theodor A. O'Leary, New York, N. Y., assignor of
forty-eight and one-third per cent to Winslow
Foster, New York, N. Y.

Application September 27, 1939, Serial No. 296,855

6 Claims. (Cl. 145—50)

This invention relates to new and useful improvements in screw drivers, and relates more particularly to an improved driver for driving a screw having a special type of slot formed in the head portion thereof.

The screw which is adapted to be driven by the driver constituting the present invention is disclosed in my copending application Serial No. 75,611, issued as Patent No. 2,182,092, such screw having a transverse slot in the head, the lower wall of the slot being concavely curved and terminating just short of the peripheral edges of such head portion. The opposed side walls of the slot are not parallel as in a conventional screw, but are upwardly and inwardly converging in the central portion only, the terminal portions of such opposed side walls being substantially parallel to each other. Thus a transverse section taken through the center of the slot would present a dove-tail effect and a relatively conventional driver for driving such a screw would include a bit portion having a curved terminal or bit portion, the opposed side walls of such bit portion being outwardly flanged to correspond generally with the side walls of the dove-tailed slot.

To employ a screw driver of this character in driving a screw of the aforementioned type, it is necessary to cause the bit to enter the slot from one end thereof, thus moving either screw or driver through a partial arc. It will thus be apparent that once the bit portions is in position in the screw slot, longitudinal displacement of the bit relative to the slot is impossible, and after the screw has been driven, the bit portion of the driver is removed from the slot in the same manner as it entered such slot.

It is one of the principal objects of the present invention to provide an improved driver for use in driving a screw of the aforesaid type, such driver having split bit portions which are longitudinally movable in a hollow shank. The lower end of the shank is formed with a wall having an aperture substantially rectangular in shape and of such size as to receive and support the two bit portions. When it is desired to drive a screw, these bit portions are moved outwardly from the lower end of such shank and means are provided for causing such bit portions to separate sufficiently to engage the screw slot at opposite ends thereof. Once in this position, the bit portions are again drawn into the shank, closing as they move inwardly, and when they have come to rest in their fully retracted position, the adjacent walls of such split bit portions are in meeting engagement and the upper sur-

face of the head of the screw is in firm engagement with the lower surface of the shank. Thus, during the driving operation the screw is maintained in rigid, axial alignment with the shank 5 of the driver and both transverse and longitudinal movement of the screw relative to the driver is prevented.

This greatly aids in the rapid driving of the screw, and when the screw has been driven fully 10 home, novel means are provided for permitting rapid release of the flanged bit portions from the screw. It is accordingly another object of the invention to provide an improved driver of this general character having a pair of split bit 15 portions firmly supported in the lower end of a shank or other supporting means, such shank further being provided with means for controlling the operation of the split bit portions at a point remote therefrom.

20 The principal embodiment of the invention illustrated in the drawing is a driver of the foregoing character adapted to be received in a chuck of a power driver, although it is quite apparent that a conventional handle could be placed upon the upper end of the shank and the driver used manually.

In the drawing:

Fig. 1 is a broken side elevation, partially in section, of the preferred embodiment of the present invention;

30 Fig. 2 is a view similar to Fig. 1, but is taken at right angles to the view shown in Fig. 1;

Fig. 3 is an elevation of the lower end of the driver;

Fig. 4 is a broken longitudinal section taken 35 on line 4—4 of Fig. 2;

Fig. 5 is a transverse section taken on line 5—5 of Fig. 4;

Fig. 6 is a view showing the two bit portions 40 in closed or operative position and the controlling mechanism of such bits, the view also showing a portion of the screw in section;

Fig. 7 is a broken, enlarged, longitudinal section of a portion of the device;

Fig. 8 is an exploded view of the bit portions 45 and the controlling means therefor;

Fig. 9 is a top plan view of a screw head having a pair of the special slots formed at right angles to each other;

Fig. 10 is a broken elevation of a driver showing the position of the split bit portions as they 50 are about to enter the screw slot;

Fig. 11 is a broken longitudinal section showing a modified form of the present invention;

Fig. 12 is similar to Fig. 11, but is taken at right 55 angles to the view shown in Fig. 11.

The preferred embodiment of the present invention is illustrated in Figs. 1 to 8, inclusive, and includes a shank structure 10 and split bit portions 11 and 12. The shank structure includes a barrel 14 and a solid shank portion 15 which is secured in the upper end of the sleeve by means of a set screw 16. The shank portion 15 illustrated in Fig. 1 is adapted to be received in the chuck of a power bit, although it will be appreciated that if a hand driver is desired, this shank portion may be more elongated and a handle secured to the upper end thereof.

At the lower end of the barrel a pair of integrally formed, opposed extension portions 18 are provided, which portions receive a flat, circular, bit supporting plate 20. This plate is formed with a rectangular opening 21 in which the bit portions 11 and 12 are positioned. The lower surface of the plate is further formed with a central, concave recess 22 to receive the upper surface of a screw in the case of a round or oval headed screw. This circular recess is, however, of lesser diameter than that of the conventional flat head 24 of a screw 31 of that character, as shown in Figs. 6 and 7, so that regardless of the shape of the upper surface of the head, the lower surface of the plate 20 is in meeting and firm engagement with such head during the driving operation.

The plate 20 is further formed with opposed, arcuate recesses 26 around the marginal edges thereof, such recesses being shaped complementary to the extensions 18 of the barrel and such extensions act to support the plate and to prevent rotative movement thereof relative to the barrel 14.

Thus it will be apparent that power applied to the shank structure 10, whether by machine or by manual means, is imparted to the plate 20 and to the side walls of the opening 21 therein, and thence to the bits. No other twisting power is applied to the bits.

Now to refer to the specific connection between the bits and the screw slot necessary to hold the screw in rigid axial alignment with the shank during the driving operation, it will be noted that the lower wall 30 of the slot in the head 24 of the screw 31 (Fig. 6) is concave and terminates short of the periphery of such head. As was earlier pointed out, the side walls 33 of the screw slot at the central portion thereof, converge inwardly, as is clearly shown in Fig. 7, and these walls progressively become more nearly parallel to each other as they approach the terminals of the slots. Thus, each bit portion 11 and 12 is formed with a tapered recess 36, also as shown in Fig. 7, and when the bits come together in the manner hereinafter described, to the position shown in Fig. 6, these tapered portions 36 reside in such dove-tail slot in the screw.

It will accordingly be apparent that when the bits have been retracted into the barrel, the upper surface of the screw head will have been drawn into firm engagement with the lower surface of the plate 20 and both longitudinal and transverse movement of the screw head relative to the bit portions is effectively prevented during the driving operation and such screw is held in relatively firm axial alignment with the shank structure 10. The plate 20 is further provided with integrally formed extensions 38, the external surface of such portions being such as to closely fit the bore of the barrel 14. It will accordingly be seen that a recess 39 is formed in the center of such barrel through which the

bit portions are free to travel. The extension portions 38 on the plate 20 are firmly secured within the bore in the barrel by means of a pin 41 passing through aligned apertures in the extension portions 38 and such sleeve, all as shown in Fig. 4.

The bit portion 12 is formed with an extension portion 44 and a pin 45 pivotally secures this portion to a longitudinally movable control rod 46 and when this rod is moved downwardly, by means hereinafter described, the bits move outwardly to their spaced, screw receiving positions. This bit portion is further formed with a slot 48 substantially in alignment with the shank when the bits are in driving position (Fig. 6). The slot is further formed with an upper extension portion 49 lying at an angle of approximately 30° to the slot 48.

The bit portions 11 and 12 are of substantially the same thickness and lie in the same plane (Fig. 3), although the extension portion 44 of bit 12 lies above a similar, though shorter, extension portion 51 of bit 11 when viewed in position shown in Figs. 4 and 6. This portion 51 is formed with a slot 52 with extension portion 53.

When the bits have been retracted into the barrel, they are maintained in meeting engagement with each other by means of engagement of the external edges with the end walls 55 of slot 21 in plate 20 (Fig. 6) and in this position the pin 41 resides at the lower end of slots 48 and 52 in portions 44 and 51. In this position, these slots are in alignment with each other.

Downward movement of rod 46, and accordingly bit portion 12, causes similar movement of bit 11 by engagement between a curved shoulder 57 at the lower end of portion 44 and a complementary portion 58 of portion 51. Similar complementary curved surfaces 57' and 58' are formed on the opposite sides of portions 44 and 51 respectively, to control movement of bit portion 11 during upward movement of bit 12.

It will be apparent that as bits 11 and 12 move downwardly, their movements are parallel until the pin 41 gets to the ends of slots 48 and 52. Further movement of the bits causes the pin to engage slots 49 and 53 which are in effect cam faces. Thus the bits separate to receive the screw slot.

In the preferred embodiment of the present invention, control means for the rod 46 are provided whereby movement of the screw head against the extended bits causes the bits to spring back into operative position and at the end of the driving operation, longitudinal movement of the driver relative to the screw causes the bits to spring outwardly, thus freeing driver from screw. These means are as follows:

A longitudinally movable rod 60, which is preferably square or otherwise non-circular in transverse section, is supported for longitudinal movement within the barrel 14 of the shank by means of a journal block 61, which is secured within the sleeve by means of a screw or pin 62, such block having a central longitudinal aperture 63 therein. This rod is secured at its lower end to the rod 46 by means of a screw 65. At its upper end, the rod 60 is preferably circular in transverse section as shown at 67 and at its upper end a number of locking nuts 68 are positioned, the lower one engaging a washer 69. This washer abuts against the upper surface of a second journal block 71 which is longitudinally movable within the barrel 14. Movement of the block 71 is controlled by means of a short sleeve 73 car-

ried on the exterior of the barrel 14, the external surface of such sleeve 13 being knurled or otherwise rendered non-smooth, as shown at 74. A pin 75 connects the sleeve 13 with the block 71, such pin passing through an irregularly shaped aperture in the barrel 14, shown clearly in Fig. 2, and having elongated diagonal portions 77 and 78. A spring 79 is mounted concentrically of the circular portion 67 of the rod 60, the lower end of the spring passing through an aperture 80 in such square rod 60. The opposite end of this spring passes into a small aperture 81 in the block 71.

The operation of this mechanism is as follows. The rod 60 is movable longitudinally but may not rotate because of square aperture 63 in the journal block 61. Journal block 71 supporting the circular portion 67 of the rod 60 may rotate within the barrel 14, although such rotative movement is accomplished against the torsion of spring 79.

When a screw is to be driven and the bit portions are fully retracted (Fig. 4) the external knurled sleeve 13 is moved downwardly, thus moving rod 46 downwardly and also the bits 11 and 12 in the same direction. This downward movement of sleeve 13 causes it to rotate as well for pin 75 must follow the opposed cam surfaces of slot 78 (Fig. 2). This rotative movement of sleeve 13 causes the spring 79 to become slightly wound. In the course of its downward movement, pin 75 passes point 84 marking the terminal of slot 78. The spring 79 performs the balance of the movement since in an effort to unwind, it causes pin 75 to ride down the cam surfaces of slot 77. The bit portions have now sprung forward to screw slot engaging position, the bit portion also having moved apart to the position shown in Fig. 10.

The screw is now moved upwardly (manual actuation of sleeve 13 is unnecessary), pushing the bit portion back into sleeve 14. The only resistance afforded against this movement is that of spring 79 which is being wound while pin 75 rides up cam surfaces of slot 77. When pin 75 passes point 84 the spring 79 does the rest and the screw is in driving position (Fig. 6). At the end of the driving operation, it is not necessary to manually operate sleeve 13 to release the screw. The driver is pulled away from the screw, the driver being maintained in axial alignment with the screw during this operation. The pin 75 re-traces its path and the bits move outwardly.

The foregoing and principal embodiment of the present invention is largely an automatic screw driver so far as actuation of the bits is concerned. The embodiment of the invention illustrated in Figs. 11 and 12 is substantially the same, except that manual non-automatic means for actuating the bits are provided. In this instance, the barrel 86 is constructed substantially the same as the barrel 14 and the bit portions (not shown) are also the same as shown in the preferred embodiment of the invention. These bit portions are controlled by means of a longitudinally movable control rod 87, which is secured at the lower end thereof to the bits, as in the preferred embodiment, and at the upper end such rod passes through an aperture 88 in a journal block 89 positioned within the barrel 86 and is adapted to move longitudinally thereof.

At its upper end, the rod 87 is provided with a locking nut 89' which engages a washer 90', which in turn engages the upper end of the block 89. The control rod 87 is not keyed to the block 89. The upper end of the barrel 86 is provided with a

conventional screw driver handle 90. Manual movement of the rod 87 is provided by means of a sleeve 91 having a longitudinal bore 92 therein adapted to receive the exterior of the barrel 86.

The external periphery of the sleeve 91 is knurled, as shown at 93. A diagonal slot 94 is formed in the sleeve, such slot having a short terminal portion 95 at the upper end thereof, such portion lying at right angles to the barrel 86. A set screw 96 passes through the sleeve 91, through the slot 94 and into the journal block 89. A collar 100 is keyed to control rod 87 and when journal block 89 is moved downwardly the control rod likewise moves. When it is desired to move the bits outwardly, the sleeve 91 is turned in the direction of the arrow shown in Fig. 11, thus causing the screw 96 to ride on the cam surface afforded by the slot 94, thus moving the rod 87 downwardly. When the screw is in place, the sleeve is turned in the opposite direction and the rod then moves upwardly, thus drawing the bit portions into the barrel. After the pin 86 has left the diagonal portion 94 of the slot and enters the straight portion 95, it becomes in effect locked in such latter portion.

The screw illustrated in Fig. 9 is the same as that shown in Figs. 6 and 7 except that the head portion 97 thereof is provided with slots 98 and 99 at right angles to each other.

It will be appreciated that the foregoing specific embodiments may be modified considerably without departing from the spirit of the invention as defined by the appended claims. Among the more important aspects of the present invention is the provision of the split bits which are adapted to move longitudinally within the lower end of the shank of the driver, means being provided for spreading the bits apart as they move outwardly or downwardly and for causing the same to come together as they move upwardly or inwardly. The bit portions shown in the preferred embodiment of the invention are pivotally mounted on a common pivot member, although if desired, these bit portions could be made entirely separate from each other, or on the other hand they could be provided with circular apertures rather than the elongated slots, and mounted together on a common pivot, and means other than those illustrated employed for spreading the bits apart. It will also be apparent that other means for supporting the bits as they move outwardly may be employed and also means other than those shown may be employed for controlling such bits. For instance, instead of employing the longitudinally movable control rod 46, a rotating member might be employed. Or, in some instances, the bits might be controlled at the lower end of the driver only.

It will further be apparent that the foregoing drivers may be used for driving screws other than those disclosed in my aforesaid co-pending application. The principal embodiment of such screw includes a slot having a concavely curved lower wall, the central portion of the side walls converging inwardly. The present driver however, may be used on a variety of screws having undercut slots in the heads thereof.

What I claim is:

1. A screw driver, adapted to drive a screw having a dovetail slot in the head thereof, comprising an elongated, hollow shank, a plate positioned at the forward end of the shank and having a substantially rectangular opening therein, a bit comprising a pair of undercut, complementary bit portions positioned within such open-

ing, said bit portions being formed with flat surfaces engaging the sides of said opening to prevent rotation therebetween, each bit portion having a longitudinal slot therein, a pin supported by the shank and passing through such slots in the bit portions, each slot having an inner extension lying at an angle to the slot whereby outward movement of the bit portions causes such portions to separate as the pin engages the slot extension portions, a longitudinally movable central rod connected with one bit portion and complementary shoulder portions formed on the several bit portions to cause them to move simultaneously.

2. A screw driver, adapted to drive a screw having a dovetail slot in the head thereof, comprising an elongated, hollow shank having a substantially rectangular opening in the forward end thereof, a bit comprising a pair of undercut, complementary bit portions positioned within such opening and having flat surfaces engaging the sides of said opening, each bit portion having a longitudinal slot therein, a pin supported by the shank and passing through such slots in the bit portion, each slot having an inner extension lying at an angle to the slot whereby outward movement of the bit portions causes such portions to separate as the pin engages the slot extension portions, manual means for causing inward and outward longitudinal movement of said bits comprising a central rod journaled within the shank for longitudinal, non-rotative movement, the shank having a substantially V-shaped slot therein, a member carried by the rod and formed with a portion lying in said slot and a spring restricting rotative movement of said member.

3. In a screw driver, adapted to drive a screw having a dovetail slot in the head thereof, the combination of a shank having a longitudinal bore therein and a substantially rectangular opening at the forward end of the shank, a bit comprising a pair of undercut, complementary bit portions positioned within such opening, said bit portions being formed with flat surfaces engaging the sides of said opening to prevent rotation therebetween, each bit portion having a longitudinal opening therein, a pin supported by the shank and passing through such openings in the bit portions, each opening having an inner extension lying at an angle to the opening, whereby outward movement of the bit portions causes such portions to separate as the pin engages the slot extension portions, and means comprising a longitudinally movable central rod for moving said bit portions outwardly.

4. In a screw driver, the combination of an elongated shank having a narrow opening in the forward end thereof and a longitudinal bore ex-

tending over the major portion of the balance of the shank, a bit comprising a pair of undercut, complementary bit portions positioned within such opening, said bit portions being formed with opposed, substantially flat surfaces engaging the sides of said narrow opening to prevent rotation therebetween, each bit portion having a longitudinal slot therein, a pin supported by the shank and passing through such slots in the bit portions, each slot having an inner extension lying at an angle to the slot whereby outward movement of the bit portions causes such portions to separate as the pin engages the slot extension portions, and manually actuated means associated with the bit portions to cause them to move simultaneously outwardly and inwardly.

5. In a screw driver, the combination of a shank having a narrow opening in the forward end thereof, and a longitudinal bore therethrough, a bit structure comprising a pair of undercut, complementary bit portions formed with substantially flat surfaces engaging the sides of the narrow opening to prevent rotation therebetween, each bit portion including a rearwardly extending plate having a cam surface comprising a longitudinal slot, and a slot extension lying at an angle to the longitudinal slot, the plates of the bit portions overlying one another, a pin fixed to said shank and passing through such slots, whereby outward movement of the bit portions causes such portions to diverge as the cam surfaces act against the pin, and inward movement of the portions causes the same to converge, and means for moving such bit portions simultaneously, inwardly and outwardly.

6. In a screw driver, the combination of a shank having a substantially rectangular opening in the forward end thereof, and a longitudinal bore therethrough, a bit structure comprising a pair of undercut, complementary bit portions formed with substantially flat surfaces engaging the sides of the narrow opening to prevent rotation therebetween, each bit portion including a rearwardly extending plate having a longitudinal slot and a slot extension lying at an angle to the longitudinal slot and forming opposed cam surfaces, the plates of the bit portions overlying one another, a fixed pin passing through such slots, whereby outward movement of the bit portions causes such portions to diverge as the cam surfaces act against the pin, and inward movement of the portions causes the same to converge, and means for moving such bit portions simultaneously, comprising a manually movable control rod mounted within the shank and secured to one of the bit portions, and complementary shoulders formed on the bit portions.

THEODOR A. O'LEARY.
